No. 798,984.

PATENTED SEPT. 5, 1905.

S. V. SHAROOD.
HEATING SYSTEM.
APPLICATION FILED SEPT. 8, 1903.

UNITED STATES PATENT OFFICE.

SAMUEL V. SHAROOD, OF BROCKTON, MASSACHUSETTS, ASSIGNOR OF ONE-HALF TO LUCIUS R. CHURCHILL, OF BROCKTON, MASSACHUSETTS.

HEATING SYSTEM.

No. 798,984.

Specification of Letters Patent.

Patented Sept. 5, 1905.

Application filed September 8, 1903. Serial No. 172,311.

To all whom it may concern:

Be it known that I, SAMUEL V. SHAROOD, a citizen of the United States, residing at Brockton, in the county of Plymouth and State of Massachusetts, have invented certain new and useful Improvements in Heating Systems; and I do declare the following to be a full, clear, and exact description of the invention, such as will enable others skilled in the art to 5 to which it appertains to make and use the same.

This invention relates to heating systems, and more particularly to vacuum steam-heating systems designed to be incorporated in steam plants using power and in which the 10 exhaust-steam from the engine is utilized for heating purposes.

In carrying my invention into effect I attach a steam-pump to the return end of the system, and by creating a vacuum in the pipes 15 the exhaust-steam from the engine, which has no back pressure, is drawn into the system, the steam not absorbed by the system being drawn toward the pump and condensed. Otherwise it would fill the upper part of the water-chamber of the pump and render the latter 20 inoperative.

In the accompanying drawings, Figure 1 is a perspective diagram of so much of a steam heating apparatus as is required to illustrate 25 the application of the invention. Fig. 2 is a perspective view of the separator and connections, a portion of said separator being broken away to show the internal construction; and Fig. 3 is a sectional view of a check-valve of usual construction which I utilize in 30 a pipe connection.

In the drawings, 1 represents the water end of a steam-pump, to which is connected one end of a suction-pipe comprising the parts 2, 35 4, and α , forming the return side of the circuit, through which the water of condensation is conducted to the pump. Also connected with the pump is the delivery-pipe 3, which conducts the heated water of condensation 40 to the boiler. (Not shown.) The loop or member 4 of the suction-pipe 2 is elevated to an extent sufficient to insure a water seal of the valves of the pump and has at the delivery-terminal of the loop a jet-condenser 45. This condenser is of simple construction, consisting of a pipe 6, screwed into the top of an upward extension 7 of the delivery end of the loop, plugged at its lower end, as shown at 8, and provided above the plug with jet-orifices 50

9 for the production of a spray to condense 55 the steam and vapor arising from the water as it is drawn into the pump. The pipe 6 has a controlling-valve 10.

A separator 11 is mounted adjacent to the pump upon a suitable supporting-standard 12 and comprises a tank or chamber 13, flanged at its upper end for the attachment of a suitable cover 14. This chamber is connected with the suction-pipe 2 by means of a pipe 15, having a swing check-valve 16 of ordinary 60 construction and a cut-off valve 17 and is also connected with the pump through a water-discharge pipe 18, provided with a cut-off valve 19. The pipe 18 communicates with the chamber 13 some distance above its bottom 65 and has a downwardly-projecting nozzle or discharge portion 20, which extends to near the bottom of said chamber and is submerged in the water contained therein.

In the top of the separator 11 a vapor-chamber 21 is mounted and is provided at its lower end, which normally lies a short distance above the level of the water in said chamber, with outlet-ports 22, controlled by needle-valves 23, carried by a stem 24, having an exteriorly-operating handle 25, said stem extending through a stuffing-box 26 in the top of said chamber 21. The said chamber 21 receives the air and vapor fed into the chamber 13 with the water and permits the 70 same to discharge to the atmosphere through a discharge-pipe 27.

The operation of my invention may be described as follows: The steam is turned on to operate the pump and to allow it to work at 75 a moderate speed at first. Then the valves 19 and 24 are opened slightly to allow the air to escape through pipe 27. Thus the pump works like an air-pump, operating against no pressure until the hot water comes. Should 80 water show at the outlet in pipe 27, the valve 17 should be slightly opened to draw this water into the system again. Then the jet 9 must be opened to supply sufficient water to keep up a steady stroke of the pump. The 85 water necessary to condense the steam at the condenser is returned to the boiler by way of the pipe α , through the pump 1, and out through pipe 3 to the boiler; but this is not sufficient to supply the amount required as a boiler-feed. The loop 4 in pipe 2 is for the purpose of forming a pocket for water to insure a 90 head of water sufficient to always keep the 95

valves of the pump submerged to secure a steady stroke of the pump, and the jet 9 at the end of the loop supplies the demand by condensing the steam as it is drawn toward 5 the pump. As the system gets thoroughly heated the jet 9 and valve 19 may be opened wider, and if there is an excess of water the valve 17 may be further opened.

From the foregoing description, taken in 10 connection with the accompanying drawings, the construction, operation, and advantages of the invention will be readily understood without requiring a more extended explanation.

15 Various changes in the form, proportion, and the minor details of construction may be resorted to without departing from the principle or sacrificing any of the advantages of this invention.

20 Having thus described my invention, what I claim, and desire to secure by Letters Patent, is—

1. In a heating system of the character described, the combination with a return-pipe, 25 of a suction and force pump, and a device connected to the suction-pipe and water-chamber of the force-pump to receive water, vapor and air from the pump above the level of the water-valves thereof, and having an independent vent for the air and vapor, the connection with the suction-pipe allowing the water therein above the normal water-level to discharge by suction to maintain a certain level, whereby the discharge and waste of 30 water is prevented, the valve of the pump kept submerged and the pump is adapted to serve as a suction-pump and boiler-feeder, substantially as described.

2. In a heating system of the character described, the combination with a suction-pipe, 40 of a pump connected with said pipe and provided with a boiler feed-pipe, and a separator connected with said suction-pipe and the water-chamber of the pump, the connection 45 with the pump opening into the bottom of said separator, the said separator being provided above the connection with the suction-pipe with a vent for the air and vapor, substantially as described.

50 3. In a heating system of the character de-

scribed, the combination with a suction-pipe, a boiler feed-pipe, a suction and force pump connected to said pipe, a separator comprising a vessel adapted to receive water and provided in its upper end with an air and vapor 55 vent, a pipe leading from below said vent to the suction-pipe, and a pipe leading from the water-chamber of the pump to the separator and extending down therein and submerged in the water therein, substantially as de- 60 scribed.

4. In a heating system of the character described, the combination of a suction-pipe, a boiler feed-pipe, a suction and force pump connected to said pipes, a cold-water injector 65 arranged in said suction-pipe, and a separator connected to the water-chamber of the pump and to the suction-pipe beyond the said injector, said separator having an air and vapor vent above the suction-pipe and pump connection and having the latter submerged in the water therein to form a seal, whereby the valves of the pump are maintained in a submerged position, substantially as de- 70 scribed.

75 5. In a heating system of the character described, the combination of a suction and force pump, a suction-pipe connected with the pump and looped adjacent thereto to extend on a higher plane, a cold-water injector disposed at 80 the delivery end of the loop, a boiler feed-pipe leading from the pump, a separator adapted to receive water, air and vapor from the water-chamber of the pump and connected with the suction-pipe at the inlet end 85 of said loop and with the water-chamber of the pump, said separator having an air and vapor vent above said connections, and the pump connection being sealed in the water therein, whereby the discharge of water and 90 breakage of the seal is prevented and the valves of the pumps maintained in a submerged position, substantially as described.

In testimony whereof I have hereunto set my hand in presence of two subscribing witnesses. 95

SAMUEL V. SHAROOD.
